COLLAPSIBLE SIGN

Robert Lee Bybee, Horseshoe Bend, Idaho

Application July 7, 1938, Serial No. 218,026

1 Claim. (Cl. 40—125)

My invention relates to improvements in signs of the collapsible type.

The invention is designed with the particular purpose in view of providing a sign structure for use in danger zones, such as where explosives are being unloaded or manufactured, and which is simple in construction, economical to manufacture, may be readily collapsed into compact form for carrying or when not in use, and easily extended for use when desired.

To the accomplishment of the foregoing, and subordinate objects presently appearing, a preferred embodiment of my invention has been illustrated in the accompanying drawings, set forth in detail in the succeeding description, and defined in the claim appended hereto.

In said drawings:

Figure 1 is a view in side elevation of my improved sign showing the same extended,

20 Figure 2 is a view in end elevation,

Figure 3 is a view in side elevation with the parts collapsed,

Figure 4 is a view in horizontal section taken on the line 4—4 of Fig. 1 looking downwardly,

25 Figure 5 is a view in transverse section taken on the line 5—5 of Fig. 1 looking in the direction indicated by the arrows,

Figure 6 is a view in longitudinal section taken on the line 6—6 of Fig. 2, and

30 Figure 7 is a view in perspective of one of the guides.

Referring to the drawings by numerals, the sign of my invention comprises a substantially elliptical base 1 of wood or any other suitable material and which is stepped to provide an enlarged lower portion 2 for imparting balance and stability to the device. The base 1 is apertured to provide an elongated chamber 4 therein the walls of which are stepped in conformity with 35 the base 1, the chamber being open at its top and closed at its bottom by a panel 5 mortised into said base and secured thereto by screws 6.

The panel 5 supports a pair of guides 7 extending along opposite sides of the chamber 4, respectively, in parallel relation and each comprising a pair of upper and lower flat bars 8 spaced apart by spacers 9 interposed between the ends thereof, said guides being anchored to said panel 5 by screws 10 extending through opposite ends thereof 40 and through said panel. The guides 7 support a pair of lazy tongs 11 having lower ends 12 pivotally mounted on a pair of rollers 13 the ends of which extend into said guides 7 and roll therein, the arrangement being such that the pair of 45 lazy tongs 11 extend upwardly from said rollers

at opposite sides of the chamber 4, respectively, to be extended vertically out of the chamber or collapsed downwardly into the same.

The upper ends of the lazy tongs 11 are connected by a laterally flanged bridge member 15 5 pivotally connected to said tongs, as at 16, to swing thereon. A suitable sign panel 17 having the appropriate legend 18 thereon shown in the drawings is fixed edgewise to said bridge member 15 by feet 19 thereon soldered to said member, 10 said panel in the normal position of the bridge member extending above the lazy tongs 11 but being swingable with said member about the pivots 16 of the latter to fold downwardly between the upper ends of said lazy tongs. 15

The manner in which the device is used will be obvious. Suffice to explain, that when it is desired to use the device the lazy tongs 11 are extended out of the chamber 4 to the desired extent and panel 17 swung into normal upstanding position to display the legend thereon. When it is desired to fold the device the panel 17 is swung downwardly between the upper ends of the lazy tongs 11 and the latter are then collapsed into the chamber 4. When fully collapsed, the lazy 25 tongs 11 are hidden in the chamber 4 likewise the panel 17 as shown in dotted lines in Fig. 3.

The foregoing will, it is believed, suffice to impart a clear understanding of the invention without further explanation. 30

Manifestly modifications in structure and arrangement of parts described may be resorted to without departing from the inventive concept and right is herein reserved to such modifications falling within the scope of the subjoined claim. 35

What is claimed is:

A device of the class described comprising a base having a chamber therein open at the top and bottom thereof, a pair of lazy tongs, means to mount said tongs in said chamber in laterally 40 spaced relation for extension and retraction out of and into said chamber comprising a plate secured to the under face of said base and closing the bottom of the chamber, a pair of guides secured to said plate in said chamber at opposite 45 sides thereof, respectively, a pair of rod-like rollers extending through corresponding ends of said tongs and into said guides, a sign bearing panel, and means pivotally mounting said panel on the other ends of said tongs for swinging movement 50 of the panel into and from an inverted position between said tongs, said plate being removable to detach the same together with the lazy tongs and said panel as a unit.
